UNITED STATES PATENT OFFICE.

ALBERT DE DION, GEORGES BOUTON, AND CHARLES TRÉPARDOUX, OF
LUTEAUX, SEINE, FRANCE.

FEEDING WATER TO BOILERS.

SPECIFICATION forming part of Letters Patent No. 329,722, dated November 3, 1885.

Application filed August 6, 1884. Serial No. 139,735. (No model.) Patented in France May 5, 1884, No. 161,912; in Belgium July 18, 1884, No. 65,806; in Germany July 22, 1884, No. 30,059; in England July 23, 1884, No. 10,492; in Italy September 30, 1884, No. 17,204; in Austria-Hungary October 5, 1884, No. 24,075 and No. 45,104, and in Spain November 15, 1884, No. 6,431.

To all whom it may concern:

Be it known that we, ALBERT DE DION, GEORGES BOUTON, and CHARLES TRÉPARDOUX, citizens of the Republic of France, and residing at Luteaux, (Seine,) France, have invented certain new and useful Improvements in Apparatus for Feeding Water to Steam-Boilers, of which the following is a full and exact description.

10 We have devised a system of apparatus which works automatically by the pressure of the steam in the boiler forcing in a sufficient quantity of water proportional to the consumption of steam, so that the water-level in the boiler shall be maintained substantially constant.

15 The steam by which the apparatus is operated is taken from the boiler at a point corresponding to the water-level which it is desired 20 to maintain.

25 The apparatus is simple, and allows the attaining of the desired end without the necessity of employing any special mechanism for regulating the feed.

30 The following is a description of what we consider the best means of carrying out the invention: We employ a piston operating in a suitable cylinder by the force of the steam, with suitable connections to a pump. The 35 pump is immersed in a tank of feed-water. The exhaust-steam from the cylinder is discharged into said tank, imparting heat to the water. When by reason of the pump having forced in a sufficient quantity of water the 40 water-level rises, a large quantity of water, instead of pure steam, will be received into the cylinder, and the action of the apparatus will be retarded to allow the water to flow through the contracted passages. The apparatus 45 will maintain a slow action under these conditions until the sinking of the water-level in the boiler again allows pure steam to be received, when the apparatus will again resume its more rapid movements.

45 The accompanying drawing forms a part of this specification, and is a side elevation of the apparatus, with a vertical section of a portion of the boiler which it is feeding.

Referring to the drawing and the letters of

reference marked thereon, A is a feed-pump 50 of the ordinary plunger style, and B is a cylinder containing a close-fitting and properly-packed piston. The piston-rod b constitutes the plunger of the pump A.

C is a stop-valve, which may be adjusted by 55 the attendant to allow the steam to be received at will from the proper point in the boiler G. Its action is controlled by suitable valves operated by a valve-stem, B', with suitable connections (not shown) from the 60 piston-rod b. It actuates the piston in the cylinder B, and consequently the pump-plunger b reciprocates rapidly and efficiently so long as dry steam is received through the valve C; but whenever the water-level M N rises so 65 that water instead of steam is received through the valve C, the water, being more sluggish in its motions, actuates the piston, and consequently the piston rod or plunger b, slowly; but its motion will continue, the cylinder B 70 taking water instead of steam from the boiler and delivering it slowly through the contracted exhaust-pipe E into the tank D. The water is pumped very slowly into the boiler. The tank D should be of sufficient size to retain the moderate quantity of water which 75 will be passed into it through the cylinder B when the water-level is momentarily too high.

Under ordinary conditions the apparatus will work with its action just sufficiently 80 choked by the presence of water in the steam to slow the action to the proper extent. It will maintain an almost absolutely uniform level of the water in the boiler, pumping always sufficiently fast to maintain a low-water 85 level in the tank D, and requiring additional water from some source, either constantly or at short intervals, to supply the loss due to the abstraction of steam from the boiler through other sources than the valves C. Such water 90 may be supplied through a cock actuated automatically by a float, J', resting on the surface of the water in D, and supplying additional water thereto from an elevated reservoir or other suitable source. In the drawings, J' 95 represents such float; J, the cock controlled thereby, and i a pipe leading from an elevated reservoir, I. It will be seen that whenever the

water-level M N rises too high by reason of the pump having forced in water faster than the consumption of steam from the boiler requires it, the cylinder B and its connections will serve 5 as a means for taking out at each stroke the small quantity of water in the boiler which is in excess. Thus not only is the pumping of the water into the boiler retarded, but also a small quantity of water is taken out of the 10 boiler by the action of the apparatus so long as the water in the boiler is in excess, but so soon as the water-level M N has again sunk the apparatus will again commence to work rapidly, and the water will be properly supplied by the 15 pump from the tank D into the boiler G, as at first. The exhaust-steam from the cylinder B, as also the hot water delivered therefrom under some conditions, insures that the feed-water in the tank D shall be at a high temperature. The fact that the feed-pump is below 20 the water-level in the tank D and is immersed in the water of the tank with a liberal communication between between the two, insures that the water is easily and promptly received 25 by the pump. It is practicable by this arrangement to pump the water at a temperature quite up to the boiling-point.

Our apparatus is certain to work slowly so soon as the water-level M N in the boiler rises, 30 and is certain to again work rapidly so soon as the water-level sinks.

Our apparatus may be applied in a great variety of conditions. It may serve with boilers of all kinds.

Instead of supplying the tank D from an 35 elevated reservoir, I, we may supply it from a street-main.

Our apparatus may be mounted at a higher level or a lower without materially interfering with its success. It may be placed at any required 40 distance from the boiler.

Our apparatus does not require especially nice adjustment. It may be an advantage under some conditions that the pump A shall be so packed and adjusted that it may leak sufficiently to prevent its pumping at all during the periods while the apparatus works slowly 45 in consequence of the water-level being already sufficiently high.

We claim as our invention— 50

In a feed-water apparatus for steam boilers, the combination, with the boiler, of a tank, as D, having the exhaust projected beneath the surface of the water therein, and having means, as J, for maintaining said water at a proper 55 level, and a pump, as A, submerged in the tank, as set forth.

In testimony whereof we have signed this specification in the presence of two subscribing witnesses.

ALBERT DE DION.

GEORGES BOUTON.

CHARLES TRÉPARDOUX.
